WALL-MOUNTED RACK FOR SUPPORTING BASEBALL EQUIPMENT

Ruby B. Williams, 54 Shallowford Road,
Chattanooga, Tenn. 37404

Filed Nov. 14, 1966, Ser. No. 4,634

Term of patent 14 years

(Cl. D33—3)

Fig. 1

I claim:

The ornamental design for a wall-mounted rack for supporting baseball equipment, substantially as shown and described.
